UNITED STATES PATENT OFFICE.

GEORGE R. WEST, OF PITTSBURGH, PENNSYLVANIA, ASSIGNOR TO THE DIAMOND
MATCH COMPANY, OF CHICAGO, ILLINOIS, A CORPORATION OF ILLINOIS.

DESIGN FOR A COMBINATION MATCH AND ASH TRAY.

60,282.

Specification for Design.

Patented Jan. 17, 1922.

Application filed December 9, 1919. Serial No. 343,605. Term of patent 14 years.

To all whom it may concern:

Be it known that I, GEORGE R. WEST, a citizen of the United States, residing at Pittsburgh, in the county of Allegheny and State of Pennsylvania, have invented a new, original, and ornamental Design for a Combination Match and Ash Tray, of which the following is a specification, reference being had to the accompanying drawing, forming part thereof.

In the drawing—

Fig. 2 is a top plan view of the combination match and ash tray and

Fig. 3 is a side elevation thereof.

I claim—

The ornamental design for a combination match and ash tray, substantially as shown.

GEORGE R. WEST.
